TELLER'S WINDOW

Eugene C. Beedle, Bay Village, Ohio, assignor to
The Guardian Burglar Proof Equipment Company, Cleveland, Ohio, a corporation of Ohio

Application April 3, 1951, Serial No. 219,046

7 Claims. (Cl. 109—19)

1

This invention relates to improvements in a bank teller's window or the like and more particularly to improvements in a teller's window for use in drive-in banking systems where the window is positioned on the outer wall of the building facing a driveway so that the occupant of a motor vehicle may complete the usual banking transactions while seated in the vehicle. These, therefore, are the general objects of the present invention.

A more specific object of this invention is the provision of a teller's window for use in connection with drive-in banking systems and which will be so arranged that both the teller and the transaction will be in full view of the customer at all times, and wherein the teller will have a full view of the approaching customer.

A further object of the invention is the provision of an improved drive-in teller's window which will keep the teller inaccessible from the outside at all times, and which may be readily constructed and installed.

According to the invention, there is provided a teller's window including a vertical frame having an enlarged window opening and a smaller opening spaced therebelow. The window opening is closed by a transparent closure while the second opening is normally closed by the front wall of an open topped receptacle. This receptacle is slidably mounted in the frame so that its open top may be made accessible from either the outer or inner face of the window as desired. A table or platform extends substantially horizontally inward from a horizontal line disposed between the two openings in the frame, and beneath which the receptacle lies when in its innermost position. The table is provided with an opening which registers with the open top of the receptacle when the front wall thereof is in position closing the frame opening. A movable closure is pivotally connected to the table and is movable to close the opening therein. Means is provided whereby the closure is locked in its closed position when the receptacle is moved outward relative to the window for the reception of a deposit by the depositor, and may not be opened until the receptacle is in its closed position. Means are also provided, to prevent withdrawal of the receptacle unless the table closure is in its closed position.

Other objects of this invention will become more apparent from the following description, reference being had to a preferred embodiment thereof illustrated in the accompanying drawings. The essential features of the invention will be summarized in the claims.

2

In the drawings, Fig. 1 is a perspective of the improved teller's window as viewed from the outside; Fig. 2 is a fragmentary sectional view in perspective, the plane of the section being indicated by the lines 2—2 on Fig. 1; Fig. 3 is a perspective view of the window removed from the wall structure and as viewed from the inside thereof; Fig. 4 is a transverse section on an enlarged scale as indicated by the lines 4—4 in Fig. 1; Fig. 5 is a transverse vertical section as indicated by the lines 5—5 on Fig. 4; Fig. 6 is a fragmentary sectional view similar to Fig. 5 but illustrating the receptacle in position to be moved to a position to be accessible from the exterior of the window; Fig. 7 is a fragmentary sectional view taken in the horizontal plane indicated by the line 6—6 on Fig. 5.

As illustrated in the drawings, the improved teller's window comprises a frame structure 10 including a plurality of channel-shaped members 11 secured together at their ends, as by welding, to form a rectangle. The flanges 12 of the channels project outwardly to facilitate the securing of the frame structure in position 20 in the walls of a building or the like. An external face plate 15 is secured as by welding to the outer face of the channels and is provided with an enlarged window opening 16 and a smaller or supplemental opening 17 which is spaced below the window opening as indicated 25 in Figs. 2 and 4. Both openings 16 and 17 lie within the confines of the rectangle formed by the channel members 11. The main opening 16 is closed by a transparent member such as a pane of heavy glass 18 which is held in position 30 against the face plate 15 by suitable securing members 19 which may be bolted or otherwise secured either to the channel members 11 or to a table portion 30 hereinafter to be more fully described.

The table 30 extends horizontally inward from the face plate 15 and is positioned between the main opening window opening 16 and the supplemental opening 17. This table is supported by and secured to the frame 10. As illustrated, 40 the table is provided with downwardly extending side and end walls 31 which are joined by a bottom wall 32. The walls 31 and 32 extend forward to the frame plate 10 and form a chamber 33 access to which is had either through the supplemental opening 17 in the frame plate or through an opening 35 in the table 30.

An open topped receptacle or drawer 40, to receive deposits, extends through the opening 17 and is slidably mounted in the frame 10 for 45 movement from a position within the chamber

33 with its front wall 41 closing the frame opening 17 and its open top 42 in registration with the opening 35 in the table, to an open position shown in Fig. 2. In its open position, the open top of the receptacle 40 extends to the outer exterior of the window to receive a deposit. The receptacle 40 is shown as being provided with rollers 44 which engage suitable guides 45 carried by the walls of the chamber 33. These rollers also may serve to prevent the full withdrawal of the receptacle from the window. The front wall 41 of the receptacle normally closes the opening 17 in the face plate 15. A supplemental rectangular frame 49 is secured to the outer face of the plate 15 and encircles the front of the drawer 40 to provide a flush external surface and prevent opening from the drawer 40 from the exterior of the window.

The opening 35 in the table 30 may be closed by a pivoted panel or door 50. This door is provided with a hinge 51 which extends along one side thereof and is secured to both the under sides of the table 30 and the door 50. When in its closed position the door 50 extends from the hinge 51 toward the edge 52 of the table 30 opposite the hinge 51. The door is spaced from the edge 52 to provide an elongated narrow slot 53 which extends substantially the full length of the panel or door 40. Adjacent its rearmost end this slot is provided with an enlarged portion 54 arranged to receive a bar 55 which is pivotally secured as at 56 to the receptacle 40. When the receptacle 40 is in its closed position the bar 55 is swung outwardly into the enlarged portion 54 of the slot by a spring 57 which is interposed between the bar and the receptacle. The upper end of the bar 55 is provided with a downwardly facing abutment 58 positioned substantially in the plane of the upper face of the table 30. Accordingly, when the door 50 is in its closed position, the bar 54 may be swung about its pivot (to the left of Figs. 5 and 7) to the position shown in Fig. 6, whereupon the teller may move the bar forwardly through the slot 53, thus moving the receptacle 40 outward to the position shown in Fig. 2. The overhanging abutment overlies the edge of the door 50 and prevents opening of the door unless the receptacle is in its closed position entirely within the chamber 33. Accordingly, a depositor will have no access to the teller through the opening 17 because of the receptacle being either in an open or partially open position.

When the receptacle is in its closed position within the chamber 33, its open top registers with the opening 35 therein.

The receptacle 40 is locked in its open position by the panel 50. This is accomplished by a bar 60 secured to the under face of the panel which, when the door and receptacle are in their closed positions, assumes the position shown in Fig. 5. When, however, the door 50 begins to open the bar 60 moves from the full line position to the dotted line position shown in Fig. 5. As the bar starts its movement towards the dotted line position, consequent upon the opening of the panel, it moves into locking engagement with the forward face of a block 65 which is secured to the side of the drawer 40 adjacent its rearmost edge. Accordingly, forward movement of the drawer or receptacle 40 is prevented unless the door 50 is in its closed position.

The front portion of the receptacle is illustrated as being provided with an inclined front

wall 48 which is visible to the depositor at all times when the door 50 is open and the receptacle in its closed position. A two-way electronic sound system may be provided, a portion of which is generally indicated at 75 as being mounted on the front face of the frame plate 16, and which permits normal conversation between the teller and the depositor.

From the foregoing it will be seen that at no time is the teller accessible from the outside of the window except through the two-way sound system, and that the teller and the apparent transaction is at all times in full view of the customer. Furthermore, inasmuch as the receptacle 40 is positioned beneath the table top it is always visible to the depositor when the cover 50 is open.

I claim:

1. A teller's window comprising, a window frame having front and rear faces together with an enlarged window opening and a supplemental opening positioned therebelow, a transparent closure for said window opening, a substantially horizontally extending table extending inward from said frame from a point above the supplemental opening and below the window opening, an open top receptacle having a front wall adapted to normally close the supplemental opening, and a drawer portion normally extending inward from the frame beneath said table, said table having an opening registering with the open top of the receptacle while the receptacle is in its normal position, a movable closure for said opening, means to support said receptacle for outward movement through said supplemental opening, means to limit the extent of the outward movement, and means to prevent outward movement of the receptacle unless said closure is in an opening-closing position.

2. A teller's window comprising, a window frame having front and rear faces together with an enlarged window opening, the supplemental opening spaced therebelow, a transparent closure for said window opening, a substantially horizontal table extending inward from said frame from a point intermediate said openings, said table having downwardly depending sides and end walls connected by a bottom wall and forming a chamber, the front of which is accessible through the supplemental opening, said table having an opening to permit access to said chamber, a receptacle slidably mounted in said chamber for movement through said supplemental opening, a door to close the opening in the table top, and means to prevent opening of said door unless the receptacle is in its closed position with its front face closing the opening in said frame.

3. A teller's window comprising, a window frame having front and rear faces together with an enlarged window opening, the second opening spaced therebelow, a transparent closure for said window opening, a substantially horizontal table extending inward from said frame from a point intermediate said openings, said table having downwardly depending sides and end walls connected by a bottom wall forming a chamber the front of which is accessible through the second-named opening, said table having an opening to permit access to said chamber, an open topped receptacle slidably mounted in said chamber for movement through said second-named opening, a movable door to close the opening in the table, means to prevent outward movement

of the receptacle unless the door is in its closed position, and means to prevent opening of said door unless the receptacle is in its closed position with its front face closing the opening in said frame.

4. A teller's window comprising, a window frame having front and rear faces together with an enlarged window opening, the second opening spaced therebelow, a transparent closure for said window opening, a substantially horizontal table extending inward from said frame from a point intermediate said openings, said table having downwardly depending sides and end walls connected by a bottom wall forming a chamber the front of which is accessible through the second-named opening, said table top having an opening to permit access to said chamber, a receptacle slidably mounted in said chamber for movement through said second-named opening, a movable door to selectively close the opening in the table top, means carried by said door and coacting with said receptacle to prevent outward movement of the receptacle unless the door is in its closed position, means to prevent opening of said door unless the receptacle is in its closed position with its front face closing the opening in said frame, and means accessible from the rear of said window to actuate said door and receptacle.

5. A teller's window comprising, a window frame adapted to be inset in a vertical wall and having an opening extending therethrough, a transparent member carried by said frame and closing said opening, a second opening extending through said frame and positioned below the first named opening, an open top receptacle having a front wall adapted to close said second-named opening, said receptacle being mounted in said frame for movement from one side or the other thereof, a substantially horizontally extending table extending inward from said frame below the first-named opening and above the second-named opening, said receptacle adapted to extend inward from said frame beneath said table, said table having an opening therein registering with the open top of said receptacle, a closure movable to and from a position to close the opening in the table, said receptacle being slidably mounted in said frame for movement to a forward position with its open top accessible from the exterior of the frame to an inward position with its open top accessible only through the opening in said table top, and means accessible from the inner face of said frame to actuate said receptacle.

6. A teller's window comprising, a window frame adapted to be inset in a vertical wall and having an opening extending therethrough, a transparent member carried by said frame and closing said opening, a second opening extending through said frame and positioned below the

first named opening, an open top receptacle having a front wall adapted to close said second-named opening, said receptacle being mounted in said frame for movement from one side or the other thereof, a substantially horizontally extending table extending inward from said frame below the first-named opening and above the second-named opening, said receptacle adapted to extend inward from said frame beneath said table, said table having an opening therein registering with the open top of said receptacle, a closure movable to and from a position to close the opening in the table, said receptacle being slidably mounted in said frame for movement to a forward position with its open top accessible from the exterior of the frame to an inward position with its open top accessible only through the opening in said table top, means to actuate said receptacle, and means to lock the closure in a closing position when the open top of the receptacle is accessible from the exterior of said frame.

7. A teller's window comprising, a window frame adapted to be inset in a vertical wall and having an opening extending therethrough, a transparent member carried by said frame and closing said opening, a second opening extending through said frame and positioned below the first-named opening, an open top receptacle having a front wall adapted to close said second-named opening, said receptacle being mounted in said frame for movement from one side or the other thereof, a substantially horizontally extending table extending inward from said frame below the first-named opening and above the second-named opening, said receptacle adapted to extend inward from said frame beneath said table, said table having an opening therein registering with the open top of said receptacle, a closure movable to and from a position to close the opening in the table top, said receptacle being slidably mounted in said frame for movement to a forward position with its open top accessible from the exterior of the frame to an inward position with its open top accessible only through the opening in said table top, means accessible from the inner face of said frame to actuate said receptacle, means to lock the closure in a closing position when the open top of the receptacle is accessible from the exterior of the frame, and means releasable from the inner face of the window to latch the receptacle in its closed position.

EUGENE C. BEEDLE.
